UNITED STATES PATENT OFFICE.

ARTHUR G. ANDERSON, OF OSAGE, MINNESOTA.

AIR-PRESSURE-GAUGE ATTACHMENT FOR INFLATING HOSE.

Application filed February 3, 1925. Serial No. 6,536.

To all whom it may concern:

Be it known that I, ARTHUR G. ANDERSON, a citizen of the United States, residing at Osage, in the county of Becker and State 5 of Minnesota, have invented certain new and useful Improvements in an Air-Pres-
sure-Gauge Attachment for Inflating Hose, of which the following is a specification.

This invention relates to an attachment 10 for the usual inflating hose employed for inflating a pneumatic tire, the attachment providing a means for supporting an air pressure gauge which is normally supported in an inoperative position on the inflating 15 hose, the same being readily adapted to be swung into an operative position for ascertaining the amount of air within the pneumatic tire.

One of the important objects of the pres- 20 ent invention is to provide an attachment of the above mentioned character, which is of such construction as to enable the same to be easily and readily associated with an inflating hose without affecting the usual 25 and ordinary use of the hose in inflating a pneumatic tire.

A still further object is to provide an attachment of the above mentioned character, which is of such construction as to 30 enable any well known type of air pressure gauge to be associated therewith, means being further provided for receiving a portion of the gauge when the same is in an inoperative position.

35 A still further object is to provide an attachment of the above mentioned character, which is simple in construction, inexpensive, and furthermore adapted for the purposes for which the same is designated.

40 Other objects and advantages of this invention will become apparent during the course of the following description.

In the accompanying drawing forming 45 part of this specification and in which like numerals designate like parts throughout the same:

Figure 1 is a side elevation of the attachment embodying my invention showing the same associated with an ordinary inflating 50 hose and with an air gauge carried by the attachment disposed in an operative position, and

Fig. 2 is a top plan view.

In the drawing wherein for the purpose 55 of illustration is shown the preferred em-

bodiment of my invention, the numeral 1 designates the free end portion of an ordinary inflating hose, the same carrying on its free end the usual inflating valve head of nozzle 2 which is adapted to be detachably 60 associated with the valve of the usual inner tube of a pneumatic tire in the manner well known in the art for the purpose of inflating said tube. An elongated bar 3 is adapt- 65 ed to be supported on the upper surface of the free end portion of the inflating hose 1 adjacent the valve head 2 through the me- dium of the adjustable clamps 4 and 5 re- spectively associated with the bar at its outer and inner end. 70

A yoke member designated generally by the numeral 6 is provided at its inner end with the extension 7, the same being pivot- 75 ally supported between the free ends of the clamp 4 on the fastening screw 8 whereby the yoke member is adapted for pivotal movement on the forward end of the bar. A fork shaped member designated generally by the numeral 9 is formed on the forward end of the yoke 6 and adapted to be detach- 80 ably supported in said fork shaped member through the medium of the adjustable thumb screw 10 which extends through the arms of the fork shaped member is an air pres- 85 sure gauge designated generally by the numeral 11, the same being of the well known construction such as is ordinarily used in ascertaining the amount of air in a pneumatic tire.

A holder 12 in the form of a substantially 90 cylindrical receptacle is associated with the inner end of the bar 3, the forward side thereof being slit as illustrated at 13 to permit the shank portion 14 of the fork shaped member 9 to be disposed in said slot so that 95 the movable gauge element of the pressure gauge will be disposed within the holder 12 in the manner shown in the dotted lines in Fig. 1 of the drawing when the air gauge is not in use. A pair of cooperating spring 100 catches 15 extend upwardly from the inner end of the bar 3 adjacent the forward part of the holder 12 and then engage the shank portion 14 of the fork shaped member 9 for preventing the accidental swinging move- 105 ment of the yoke 6 and the air gauge carried by the fork shaped member during the ordinary use of the air inflating hose.

Whenever it is desired to ascertain the air pressure of a pneumatic tire which has been 110

inflated, the yoke 6 is swung upwardly on its pivot so that the gauge 11 will be moved outwardly from the holder 12 and the yoke member 6 is of such construction as to permit the same to swing over the upper portion of the valve head 2. A cross piece 16 is provided on the yoke member 6 and engages the top of the valve head for limiting the downward movement of the yoke member 10 with respect to said valve head. A pair of cooperating spring catches 17 are provided at the forward end of the bar 1 for cooperation with the extension 7 formed on the rear or inner end of the yoke 6 for preventing the accidental upward swinging movement of the yoke during the use of the air gauge. The air gauge 11 will be supported in the position as shown in Fig. 1 of the drawing in spaced relation with respect to the valve head 2 so that the same may be readily placed on the valve stem of the usual inflating valve of a pneumatic tire inner tube in the manner well known in the art whereby the amount of air placed in the inner tube may be readily ascertained.

After the tire gauge has been used, the same is returned to its normal position within the holder 12 so that the inflating hose may be used without any interference by the 30 air gauge. Each of the aforementioned elements are adapted to be used independently.

The simplicity in which the present invention is constructed enables the device to be readily attached to an ordinary inflating hose without necessitating any alteration of the hose and furthermore any suitable air gauge may be associated with the attachment as may be desired.

Furthermore the provision of an attachment of the above mentioned character, will save considerable time and labor and will at all times be at the disposal of a person using the air inflating hose. An attachment of the above mentioned character, is particularly 45 adapted to be used at gasoline filling stations, or stores selling tires as well as other automobile accessories and where an air inflating hose is provided.

While I have shown the preferred embodiment of my invention, it is to be understood that various changes in the size, shape and arrangement of parts may be resorted to without departing from the spirit of the invention and the scope of the appended 55 claims.

Having thus described my invention, what I claim as new is:—

1. An air gauge attachment for an inflating hose comprising a bar supported on said hose adjacent the usual inflating valve head carried by the free end of the hose, a yoke member pivotally supported at one end on the forward end of said bar, means at the 60 opposite end of said yoke member for supporting an air gauge in a vertical position,

said yoke being normally disposed over said bar to hold the air gauge in an inoperative position, said air gauge being disposed in an operative position when the yoke member is swung outwardly over the inflating valve head, and means for holding the air gauge when the same is disposed in normal inoperative position, said means comprising an open top receptacle supported on the inner end of said bar. 75

2. An air gauge attachment for an inflating hose comprising a bar supported on said hose adjacent the usual inflating valve head carried by the free end of the hose, a yoke member pivotally supported at one end on the forward end of said bar, means at the opposite end of said yoke member for supporting an air gauge in a vertical position, said yoke being normally disposed over said bar to hold the air gauge in an inoperative position, said air gauge being disposed in an operative position when the yoke member is swung outwardly over the inflating valve head, means for holding the air gauge when the same is disposed in normal inoperative position, said means comprising an open top receptacle supported on the inner end of said bar, and means for preventing the upward swinging movement of the yoke member 95 when the air gauge is in said receptacle.

3. An air gauge attachment for an inflating hose comprising a bar supported on said hose adjacent the usual inflating valve head carried by the free end of the hose, a yoke member pivotally supported at one end on the forward end of said bar, means at the opposite end of said yoke member for supporting an air gauge in a vertical position, said yoke being normally disposed over said bar to hold the air gauge in an inoperative position, said air gauge being disposed in an operative position when the yoke member is swung outwardly over the inflating valve head, and means for preventing any relatively vertical movement of the yoke member when the air gauge is disposed in an operative position. 105

4. An air gauge attachment for an inflating hose comprising a bar supported on said hose adjacent the usual inflating valve head carried by the free end of the hose, a yoke member pivotally supported at one end on the forward end of said bar, a fork shaped member carried by the opposite end of said yoke, means associated with said fork shaped member for supporting an air gauge in a vertical position, an open top holder supported on the inner end of said bar and adapted to receive said air gauge 115 when the same is in an inoperative position and the yoke is disposed over said bar, means for holding said yoke member against upward swinging movement when disposed in an inoperative position, said yoke member 120

adapted to be swung over said valve head whereby the air gauge is disposed in an operative position.

5. An air gauge attachment for an inflating hose comprising a bar supported on said hose adjacent the usual inflating valve head carried on the free end of the hose, a yoke member pivotally supported at one end on the forward end of said bar, a fork shaped member carried by the opposite end of said yoke, means associated with said fork shaped member for supporting an air gauge in a vertical position, an open top holder supported on the inner end of said bar and adapted to receive said air gauge when the same is in an inoperative position and the yoke is disposed over said bar, means for holding said yoke member against upward swinging movement when disposed in an inoperative position, said yoke member adapted to be swung over said valve head whereby the air gauge is disposed in an operative position, and a cross seat associated with the yoke and engaging the top of the valve head when the air gauge is in an operative position for limiting the downward swinging movement of the yoke member.

6. An air gauge attachment for an inflat-

ing hose comprising a bar supported on said hose adjacent the usual inflating valve head carried on the free end of the hose, a yoke member pivotally supported at one end on the forward end of said bar, a fork shaped member carried by the opposite end of said yoke, means associated with said fork shaped member for supporting an air gauge in a vertical position, an open top holder supported on the inner end of said bar and adapted to receive said air gauge when the same is in an inoperative position and the yoke is disposed over said bar, means for holding said yoke member against upward swinging movement when disposed in an inoperative position, said yoke member adapted to be swung over said valve head whereby the air gauge is disposed in an operative position for limiting the downward swinging movement of the yoke member, and means for preventing the upward swinging movement of the yoke member when said air gauge is in operative position.

In testimony whereof I affix my signature.

ARTHUR G. ANDERSON.
